Inventor

John C. Schooley

UNITED STATES PATENT OFFICE.

JOHN C. SCHOOLEY, OF NEW YORK, N. Y.

IMPROVED REFRIGERATOR.

Specification forming part of Letters Patent No. 41,098, dated January 5, 1864.

To all whom it may concern:

Be it known that I, JOHN C. SCHOOLEY, of the city, county, and State of New York, have invented a new and useful improvement in refrigerators or preserving-rooms, for the preservation of meats, provisions, fruits, vegetables, and any organic substance from decomposition, or the usual effects of warm and damp weather; and I do hereby declare that the same is fully described and represented in the following specification and accompanying drawing, letters, figures, and references thereof. Figure 1 is a vertical section of my improved refrigerator, representing a refrigerator in a chest form, with the ice-chamber at the top of one end.

My invention relates more particularly to that kind of a refrigerator, either of chest or any other form, in which the air for ventilation is passed over the immediate surface of the ice-meltings instead of over the ice.

The great object of my invention, as herein described, is to prevent the contamination of the contents of a refrigerator by contact with impure and stagnant air, produced by employing the immediate surface of ice-meltings to refrigerate and ventilate the refrigerator.

During mild winters, when ice is scarce, it is often gathered from shallow ponds of still and impure water, and such kind of ice is often supplied to families. This is mostly the case throughout the Middle and Western States. When this description of ice is used in a refrigerator, the meltings will retain more or less of the original impurity of the water and emit a smell that, if allowed to be taken up by a current of air, will contaminate milk, butter, and other such articles over which it flows. To obviate this difficulty, in all refrigerators ventilated by passing air over the immediate surface of the meltings I construct a conduit opening into the provision-chamber, which I submerge in the meltings of the ice underneath the ice-chamber and through which I pass the air, which is cooled in its passage by the ice-meltings coming in contact with the outer surface of the conduit, thus preventing the passing air from taking up any bad smell from the meltings. This air then passes immediately into the preserving-chamber without coming in contact with the surface of ice or entering the ice-chamber.

In order that my improvement may be bet-

ter understood, and that others may be enabled to construct it, I refer to the annexed drawing and letters and figures of reference marked thereon.

A is the ice-chamber; B, the preserving-chamber. C is the exit air-opening. D is the opening for admission of the outer air, both covered with suitable registers, and to be opened and closed when desired.

E E' E' are conduits or air-passages, constructed either within the preserving-chamber or within the space between the inside and outside boxes, through which the warm air in the provision-chamber B will pass into the lower submerged conduit.

F F is a conduit underneath the ice-chamber, and is submerged in the meltings. G is the drain-pipe extending some distance above the water-floor, and so arranged that the meltings will sufficiently accumulate as to submerge the conduit F F before it runs off.

H H is the partition dividing the ice-chamber from the provision-chamber, which is made open or solid, as may be desired. K K is the open bottom of the ice-chamber.

When ice is placed in the ice-chamber A, and the same protected with blankets or cloths to prevent any air from coming in contact with it, thus retarding the decay, my improved refrigerator operates as follows—viz: The contained air within the refrigerator becoming cold, like in any tight apartment wherein ice is placed, will be warmer at a point at the top farthest away from the ice than at the bottom. When the registers are closed at C and D the warmer air contained in the preserving-chamber being at the top will enter the conduit E E at C from the inside, pass through the conduits E E' E', thence into the submerged conduit F F, and after becoming cooled therein in its passage it will flow directly into the provision-chamber B without passing into or through the ice-chamber, then taking up the heat from the provisions, over which it flows, will pass again through C into E E, and so will continually rotate and circulate through the provision-chamber B and conduit F F until the inclosed air becomes of the same temperature. Then it is found necessary to admit a current of outside air in order that the inclosed air may be kept in motion and an equilibrium prevented, which is done by removing the reg-

isters covering openings C and D, when the outside air will enter at D, descend through E' E', pass through and become cooled in conduit F F, and flow directly into and through the preserving-chamber and escape into the outer air at C.

The black darts show the course of the current when the outside air is used, and the red darts show the current when the registers are closed and the inclosed air is revolving.

In constructing an upright-formed refrigerator with ice at the top, and one in which the entire provision-chamber is underneath the ice-chamber, the conduit E E is not used.

Having thus fully described my improvement, what I claim as my invention, and desire to secure by Letters Patent, is—

The conduit F F, so arranged that the air passing through it will become cooled, and will flow into the preserving-chamber without coming in contact with the ice or entering the ice-chamber, substantially as and for the purposes set forth.

JOHN C. SCHOOLEY.

In presence of—

JAS. R. WALLS,

HENRY B. PIERCE.
